DEEP WELL PUMP

James Phillip Jackson, Oklahoma City, Okla.

Application October 17, 1934, Serial No. 748,703

26 Claims. (Cl. 103—46)

This invention relates to improvements in deep well pumps of the type adapted to be actuated by fluid under pressure supplied from a remote point, so that operation of the pump will be effected without the use of sucker rods and the like.

An object of the present invention is to provide an improved pump of the above type especially advantageous for use in pumping liquid from wells, and in which the motivating fluid may be conducted through the well casing to the pump mechanism for effecting actuation thereof, and also in which the exhausted motivating fluid may be discharged through the usual liquid discharge pipe together with the liquid being pumped so as to obviate the use of independent conduits for conducting such motivating fluid and liquid from the pump and so that the exhausted motivating fluid will serve to assist in lifting the pumped liquid.

Another object is to provide a pump of the above kind in which a plurality of pistons are utilized both as fluid actuated and pumping pistons, thereby obviating the necessity of separate pumping and motor cylinders and pistons with separate valve mechanisms.

A more specific object of the present invention is to provide a pump of the above kind in which two pistons are alternately and directly actuated by the fluid under pressure for pumping the liquid from the well, and whereby the actuation of each piston in one direction for forcing the liquid from the well causes retraction of the other piston to the start of its pumping stroke.

Still another object is to provide a pump of the above type in which a novel and efficient valve mechanism is provided for controlling the supply and exhaust of the pressure fluid for alternate actuation of the pistons.

Still another object is to provide a pump of the above type embodying a plurality of combined motor and pumping pistons, and in which the parts are so constructed and arranged as to adapt the pump to be operated in a space of small diameter such as is available in wells.

Other objects and advantages of the invention will become apparent as the nature of the same is better understood, and the invention consists in the novel form, combination and arrangement of parts hereinafter more fully described, shown in the accompanying drawings and claimed.

In the drawings, wherein like reference characters indicate corresponding parts throughout the several views,

Figure 1 is a fragmentary view partly broken

away and partly in section and partly in elevation, illustrating a pump embodying the present invention operatively arranged within the casing of a well.

Figure 2 is an enlarged horizontal section on line 2—2 of Figure 3.

Figure 3 is a fragmentary vertical section on the plane of line 3—3 of Figure 2, and drawn on a reduced scale.

Figure 4 is a view somewhat similar to Figure 10 3 taken on the plane of line 4—4 of Figure 2.

Figure 5 is a view similar to Figure 3 taken on the plane of line 5—5 of Figure 2.

Figure 6 is a horizontal section on line 6—6 of Figure 3.

Figure 7 is a horizontal section on line 7—7 of Figure 3.

Figure 8 is a horizontal section on line 8—8 of Figure 3.

Figure 9 is a horizontal section on line 9—9 of Figure 3.

Figure 10 is a horizontal section on line 10—10 of Figure 4.

Figure 11 is an enlarged bottom plan view of the inner or lower head for the cylinder block 25 of the pump.

Figure 12 is an elevational view, partly broken away and in section, of one of the piston-actuated push rods.

Figure 13 is a fragmentary detail section on line 13—13 of Figure 9.

Figure 14 is a view similar to Figure 13, taken on line 14—14 of Figure 9; and

Figure 15 is a fragmentary detail section showing a modification of the means for operatively connecting the pistons.

Referring in detail to the drawings, C indicates generally a well casing, and D indicates a liquid discharge pipe which extends downwardly into the well casing C and to the lower end of which is connected the pump embodying the present invention and generally indicated at P.

As illustrated, the pump P includes an elongated cylindrical block 5 formed with a pair of adjacent vertical or longitudinal bores 6 and 7 45 constituting pump and motor cylinders in which are fitted reciprocable pistons 8 and 9 having rigid depending piston rods 10 and 11 whose lower ends are operatively connected by a chain or other flexible member 12 which passes around a pulley or other guide 13 arranged a suitable distance below the block 5. Attached to the lower end of the block 5 is a tubular casing 14 into which the piston rods 10 and 11 project, the guide 55

or pulley 13 being journaled on the lower end of a support 15 projecting downwardly into the casing 14 and rigid with and depending from a plate 16 seated in the upper end of casing 14 and 5 clamped against the lower end of block 5 by means of said casing 14. The block 5 is provided with suitable stuffing boxes 17 and 18 where the piston rods 10 and 11 project downwardly therethrough, so as to prevent leakage of the motivating fluid 10 around said piston rods from the cylinders 6 and 7 into the casing 14, as will later become apparent. The lower end of casing 14 has a stem 19 15 attached thereto, which stem may carry a suitable anchor (not shown) for properly positioning and steadyng the pump at the point to which it is lowered within the well casing C.

Formed in the upper end of cylinder block 5 are longitudinal liquid passages 20 and 21 which 20 communicate at their lower ends with the upper ends of cylinders 6 and 7, and which open at their upper ends through the top of the cylinder block 5. The upper end of cylinder block 5 is further provided with lateral liquid intake ports 25 communicating with the liquid passages 20 and 21 and controlled by inwardly opening and outwardly seating check valves 22 and 23 for controlling the supply of the liquid to be pumped from the well casing about the pump into the cylinders 6 and 7 above the pistons 8 and 9. Specifically, the check valves 22 and 23 permit 30 the liquid to be drawn into the cylinders upon the downward or suction strokes of pistons 8 and 9, but close upon the upward or pumping strokes of the pistons so as to cause the liquid to 35 be forced from the cylinders outwardly through the liquid outlet passages 20 and 21. Seated on the upper end of cylinder 5 is an inner or lower cylinder head 24 provided with vertical passages 25 and 26 registering with the passages 20 and 40 21, and seated upon the inner or lower cylinder head 24 is an outer or upper cylinder head 27 also provided with longitudinal or vertical passages 28 and 29 registered with the passages 25 and 26 of the lower head 24. These heads 24 and 45 27 are clamped upon the upper end of the cylinder block 5 by means of a cap 30 removably secured on the upper end of the cylinder block 5 and to the upper end of which is connected the lower end of the liquid discharge pipe D, said cap 30 having an internal shoulder intermediate its ends 50 which engages the top of the upper head 27 as clearly shown in Figure 3. This arranges the heads 24 and 27 in the lower portion of cap 30, and provides a chamber 31 within the upper end of cap 30 above the heads 24 and 27 for a purpose which will later become apparent. Short pipes 32 and 33 are threaded in the passages 20 and 21 of the block 5 and project upwardly through the 55 passages 25 and 28 and 26 and 29 and then through the chamber 31 and the top of cap 30 so as to terminate a short distance above the latter within the liquid discharge pipe D. Thus, liquid pumped from the cylinders 6 and 7 is discharged through 60 passage 20 and pipe 32 or passages 21 and pipe 33 into the liquid discharge pipe D at a point above the top of cap 30, to be ultimately forced upwardly through the discharge pipe D to the surface of the well.

70 The pipes 32 and 33 are made in sections, the lower sections thereof having heads 32a and 33a engaging the top of upper head 27 to clamp the heads 24 and 27 together and to the cylinder block 5, and the intermediate sections thereof 75 having heads 32b and 33b engaging the top of

cap 30 to clamp the latter to the heads 24 and 27 and the cylinder block.

As shown more clearly in Figure 3, longitudinal passages 34 and 35 are provided in the cylinder block 5 and are respectively connected at their 5 lower ends by lateral passages 36 and 37 (see Fig. 10) with the lower ends of cylinders 7 and 6. These longitudinal passages 34 and 35 communicate at the upper end of the cylinder block 5 through ports 34a and 35a (Figs. 9 and 13) with 10 valve chambers 38 and 39 (Figs. 3 and 11) provided in the lower cylinder head 24 and communicating with longitudinal passages 40 and 41 provided in the upper cylinder head 27 and opening through the top of the latter into the chamber 31 in the top of cap 30. Also provided in the cylinder block 5 are longitudinal bores 42 and 43 which open at their lower ends into the upper ends of the respective cylinders 6 and 7 and communicate at their upper ends through the top 20 of the cylinder block with passages 44 and 45 provided in the lower cylinder head 24 as shown clearly in Figure 5. The passages 44 and 45 communicate with a recess or chamber 46 provided in the upper cylinder head 27, and extending 25 downwardly into the well from a suitable source of supply of fluid under pressure such as an air or gas compressor (not shown) is a fluid pressure supply pipe 47 which passes through the top of cap 30 and connects with the top of upper cylinder head 27 so as to open into passages 46a and 46b communicating with opposite sides of chamber 46. This fluid pressure supply pipe 47 is preferably provided with a suitable downwardly opening and upwardly seating check valve 48. Formed 35 in the lower cylinder head 24 above the chamber 46 are valve seats 49 and 50 on which slidably mounted plug valves 51 and 52 seat for controlling the flow of fluid under pressure from chamber 46 to the respective passages 44 and 45. These 40 valves 51 and 52 are interconnected by a rocking lever 53 and connecting rods 54, the lever 53 being pivoted intermediate its ends to an upstanding post 55 rigid with the lower cylinder head 24 and projecting upwardly into the head 27. Longitudinally 45 slidable push rods 56 and 57 are arranged in the passages 42 and 44 and 43 and 45, respectively. Each of these push rods consists of a lower section snugly slidably fitted in the passage 42 or 43 and an upper section projecting 50 upwardly through the passage 44 or 45 for engagement with the under side of the associated valve 51 or 52. Also, the push rods are made longitudinally yieldable by slidably fitting the lower ends of the upper sections of said push rods 55 within the upper ends of the associated lower sections thereof, and interposing a spring 58 between the sections as shown clearly in Figure 12. Springs 59 and 59a normally force the push rods 60 56 and 57 downwardly so that their lower ends project into the upper ends of the cylinders 6 and 7, whereby when either piston 8 or 9 moves upwardly it will engage the push rod projecting into its cylinder and force such push rod upwardly to elevate and thereby open the associated valve 51 65 or 52, the other of these valves being simultaneously forced downwardly to closed position through the medium of the connection composed of lever 53 and connecting rods 54. The operating fit of the lower sections of the push rods in 70 the passages 42 and 43 minimize leakage of fluid under pressure past the same into the upper ends of the cylinders 6 and 7, and the longitudinally yieldable nature of the push rods permits them to collapse slightly should the same be necessary 75

to allow the pistons to complete their upward strokes after the valves 51 and 52 are respectively completely seated or unseated. The longitudinally yieldable nature of the push rods also has the advantage of absorbing shocks incident to sudden contact of the pistons therewith.

As shown more clearly in Figures 9, 13 and 14, inclined ports 60 and 61 are provided to place the lower ends of the passages 44 and 45 and the upper sides of passages 42 and 43 in communication with interior of socketed plugs 60' and 61' fitted in the upper ends of the longitudinal passages 34 and 35 of the cylinder block 5. It will be noted that the ports 34a and 60 extend through the block and plug 60', while the ports 35a and 61 extend through the block 5 and plug 61' (Figures 9, 13 and 14).

Arranged in the valve chambers 38 and 39 and depending into the sockets of plugs 60' and 61' are seating valves 62 and 63 having stems 64 and 65 projecting upwardly through the passages 40 and 41 and connected by a rocking lever 66 suitably pivotally mounted within the chamber 31. It is particularly noted that the inclined ports 34a and 35a open through the top of block 5 at the bottoms of valve chambers 38 and 39 and outwardly of opposite sides of the valves 62 and 63, whereby the latter will not interfere at any time with flow of fluid under pressure from passages 44 and 42 and 43 and 45 through said ports 34a and 35a into passages 34 and 35. Said valves 62 and 63 therefore simply control the flow of motive fluid under pressure outwardly from passages 34 and 35 to passages 40 and 41 when exhausted from the respective cylinders 7 and 6 behind or beneath the respective pistons 9 and 8. It will still further be noted that fluid under pressure is admitted to the chambers 38 and 39 alternately or at different times. Thus, when fluid under pressure is admitted to passage 35 by way of port 61 and ports 35a, it will first enter the socket of plug 61' beneath the valve 63, thereby forcing said valve 63 upwardly to seating position and causing unseating of valve 62 through the operative connection 64, 65 and 66. The reversal of this operation will of course take place when the fluid under pressure is admitted to passage 34, the same first entering the socket of plug 60' through port 60 and beneath valve 62. Obviously, when valve 62 is thus raised and seated and fluid under pressure is supplied to passage 34 it will flow into the lower end of cylinder 7 so as to force the piston 9 upwardly, thereby causing the latter piston to forcibly discharge the liquid ahead of the latter from the cylinder 7. At the same time, the piston 8 is caused to lower and the air or used motive fluid behind or beneath said piston 8 is forced by the latter out of the lower end of cylinder 6 by way of passages 37 and 35, ports 35a and valve chamber 39 into passage 41 and thence into chamber 31. At this time the valve 63 will be seated in plug 61' and the valve 52 will be closed so that the exhausting fluid may not pass from passage 35 by way of port 61 and passage 45 into chamber 46. On the other hand, when the piston 9 has reached its uppermost position as shown in Figure 5, it will have actuated push rod 57 so as to open valve 52 and close valve 51, thus cutting off the supply of fluid pressure to the bottom of cylinder 7 and admitting fluid under pressure to the bottom of cylinder 6 by way of passages 45 and 43, port 61, valve chamber 39, ports 35a, and passages 35 and 37. As the fluid under pressure enters the socket of plug 61' from port 61 and beneath valve 63, the latter is forced

upwardly to seated or closed position and valve 62 is simultaneously opened. The piston 8 then rises, forcing the liquid from the upper portion of cylinder 6 and cause the piston 9 to lower, the fluid behind or below the piston 9 exhausting from cylinder 7 by way of passages 36 and 34, ports 34a, valve chamber 38, and passage 40 into chamber 31. This cycle of operation continues as long as fluid under pressure is supplied to chamber 46 by way of pipe 47, the valve and piston actuation being entirely automatic. It will of course be understood that the liquid to be pumped to the surface of the well will be drawn through the check valves 22 and 23 into the upper ends of cylinders 6 and 7 on the downward or suction strokes 15 of the pistons 8 and 9.

It will be noted that the fluid under pressure is exhausted from the cylinders into the chamber 31, and is allowed to escape from the latter through a plurality of check valves 67 provided in the top of cap 30, said check valves 67 being upwardly opened under the influence of the fluid under pressure within the chamber 31. When the pump is not in operation, the check valves 67 will normally close to prevent flow of liquid from the pipe D into the chamber 31. Also, as the liquid pumped from the cylinders 6 and 7 is discharged from the pipes 32 and 33 into the liquid discharge pipe D at a point some distance above the cap 30 and above the point where the exhausted pressure fluid escapes from chamber 31 through check valves 67 into said discharge pipe D, said exhausted pressure fluid will assist in lifting the pumped liquid and no independent conduit is necessary for conveying the exhausted pressure fluid from the pump.

Assuming that the parts are positioned as shown in the several views, the fluid under pressure will flow from pipe 47 into chamber 46, thence past valve 52 into passage 45, then by way of port 61, valve chamber 39 and ports 35a to passage 35, and thence by way of passage 37 into the lower end of cylinder 6 behind piston 8. The fluid under pressure entering plug 61' will seat valve 63 and open valve 62. As the piston 8 is forced upwardly, it will force the fluid from the upper portion of cylinder 6 as before mentioned and will cause downward movement of piston 9. As piston 9 moves downwardly it will force the fluid behind the same from the lower portion of cylinder 7 into chamber 31 by way of passages 36 and 34, ports 34a, valve chamber 38 and passage 40, the exhausted motivating fluid ultimately discharging into the lower end of pipe D through check valves 67 and beneath the liquid being discharged into pipe D from the pipe 32. As the piston 8 nears its upward limit of movement it engages push rod 56 to move the same upwardly and cause opening of valve 51 and closing of valve 52. In this way the supply of motivating fluid is cut off from cylinder 6 and allowed to flow to cylinder 7 beneath the piston 9 which has been lowered, such motivating fluid flowing to cylinder 7 by way of passage 44, port 60, valve chamber 38, ports 34a, and passages 34 and 36. As the motivating fluid enters plug 60' it closes valve 62 and opens valve 63, and as piston 9 is elevated piston 8 is lowered, the fluid being forced by piston 8 from the lower end of cylinder 6 into chamber 31 by way of passages 31 and 35, ports 35a, valve chamber 39, and passage 41. The exhausted motivating fluid entering chamber 31 from passage 41 then flows through check valves 67 into the lower end of discharge pipe D below the liquid forced from 70

cylinder 7 by piston 9 and discharged into pipe D some distance above the cap 30. Thus, each time liquid is discharged from one of the cylinders, motivating fluid is exhausted from the other cylinder, and the exhausted motivating fluid is discharged into the pipe D below the liquid discharged therein, so as to assist in lifting the latter. As before stated, this cycle of operation is continuously repeated as long as motivating fluid is supplied to chamber 46.

Any suitable means may be employed for operatively connecting the pistons 8 and 9, so that when either piston is actuated by fluid pressure to force the liquid from its cylinder, the other piston will be given its suction stroke in the opposite direction to draw liquid into the cylinder of the latter piston. For instance, the piston rods may be in the nature of racks as shown at 11a and 11a in Figure 15, said racks meshing with opposite sides of a pinion 10 journaled on the lower end of a rod 15a similar to rod 15 of Figure 4.

While I have shown and described a specific embodiment of my invention, I do not limit myself to the exact details of construction and arrangement shown, but may employ such changes in the construction and arrangement of parts, should occasion so require, as fairly come within the meaning and scope of the appended claims.

30 What I claim as new is:

1. In a pump, a pair of adjacent cylinders, a piston in each cylinder, pumping chambers in said cylinders at the outer sides of the pistons therein, means operatively connecting said pistons whereby outward movement of either piston will cause inward movement of the other piston, means for supplying motive fluid to said cylinders at the inner sides of the pistons therein for causing alternate outward movement of said pistons, 35 valves for controlling the exhaust of motive fluid from said cylinders, means interconnecting said valves whereby closing of one will cause opening of the other, and means whereby the motive fluid supplied to either cylinder will cause closing 40 of the exhaust controlling valve of such cylinder and opening of the exhaust controlling valve of the other cylinder.

2. In a pump, a pair of adjacent cylinders, a piston in each cylinder, pumping chambers in said cylinders at the outer sides of the pistons therein, means operatively connecting said pistons whereby outward movement of either piston will cause inward movement of the other piston, means for supplying motive fluid to said cylinders at the inner sides of the pistons therein for causing alternate outward movement of said pistons, said motive fluid supplying means including valves for controlling the supply of the motive fluid to said cylinders, means interconnecting 55 said valves whereby opening of one will cause closing of the other, and reciprocable push rods projecting into said cylinders for alternate actuation by said pistons on their outward pumping movements for actuating said valves to cut off the supply of motive fluid from either cylinder when the piston therein approaches its outward limit of movement and to simultaneously permit supply of the motive fluid to the other cylinder as the piston in the latter approaches its inward 60 limit of movement.

3. In a pump, a pair of adjacent cylinders, a piston in each cylinder, pumping chambers in said cylinders at the outer sides of the pistons therein, means operatively connecting said pis-

tons whereby outward movement of either piston will cause inward movement of the other piston, means for supplying motive fluid to said cylinders at the inner sides of the pistons therein for causing alternate outward movement of said pistons, a liquid discharge pipe connected to the upper ends of said cylinders, means for conducting the liquid pumped from the cylinders and discharging it at an elevated point within said discharge pipe, and means for conducting and 10 discharging the exhausted motive fluid from the cylinders into said liquid discharge pipe at a point below the point of discharge of the pumped liquid therein.

4. In a pump, a pair of adjacent cylinders, a piston in each cylinder, means connecting said pistons, pumping chambers in said cylinders at the outer ends of said pistons, means for supplying motive fluid to said cylinders at the inner ends of the pistons for causing movement of the pistons, valves for controlling the exhaust of motive fluid from said cylinders, and means whereby the motive fluid supplied to either cylinder will cause closing of the exhaust controlling valve of such cylinder and opening of the exhaust controlling valve of the other cylinder.

5. In a pump, a pair of adjacent cylinders, a piston in each cylinder, pumping chambers in said cylinders at the outer ends of said pistons, means for supplying motive fluid to said cylinders at the inner ends of the pistons for causing movement of the pistons, valves for controlling the exhaust of motive fluid from said cylinders, means whereby the motive fluid supplied to either cylinder will cause opening of the exhaust controlling valve of the other cylinder, and flexible means connecting said pistons whereby movement of one piston under power of motive fluid will move the other piston.

6. In a pump, a pair of adjacent cylinders, a piston in each cylinder acting as a pumping piston and a power piston, means connecting said pistons, means for supplying motive fluid to said cylinders at one end of said pistons, valves for controlling the supply of motive fluid to said cylinders, and independent means operated by each piston for operating the valves controlling the delivery of motive fluid to the cylinders, said valve operating means and said valves arranged whereby each piston will actuate the valves to cut off the supply of motive fluid to its cylinder and open the supply to the other cylinder.

7. In a pump, a pair of adjacent cylinders, a piston in each cylinder acting as a pumping piston and a power piston, means connecting said pistons, means for supplying motive fluid to said cylinders at one end of said pistons for causing movement of the pistons, valves for controlling the supply of motive fluid to said cylinders, independent means operated by each piston for operating the valves controlling the delivery of motive fluid to the cylinders, valves for controlling the exhaust of motive fluid from said cylinders, and means whereby the motive fluid supplied to either cylinder will cause closing of the exhaust controlling valve of such cylinder and the opening of the exhaust controlling valve of the other cylinder.

8. In a pump, a pair of adjacent cylinders, a piston in each cylinder acting as a pumping piston and a power piston, means connecting said pistons, means for supplying motive fluid to said cylinders at one end of said pistons, valves for controlling the supply of motive fluid to said cylinders, independent means operated by each pis-

- ton for operating the valve controlling the delivery of motive fluid to the cylinders, said valve operating means and said valves arranged whereby each piston will actuate the valves to cut off 5 the supply of motive fluid to its cylinder and open the supply to the other cylinder, valves for controlling the exhaust of motive fluid from said cylinders, and means whereby the motive fluid supplied to either cylinder will cause opening of 10 the exhaust controlling valve of the other cylinder.
9. In a pump, a pair of adjacent cylinders, a piston in each cylinder acting as a pumping piston and a power piston, means connecting said 15 pistons, means for supplying motive fluid to said cylinders at one end of said pistons, valves for controlling the supply of motive fluid to said cylinders, independent means operated by each piston for operating the valves controlling the delivery 20 of motive fluid to the cylinders, valves for controlling the exhaust of motive fluid from said cylinders, means whereby the motive fluid supplied to either cylinder will cause closing of the exhaust controlling valve of such cylinder and 25 the opening of the exhaust controlling valve of the other cylinder, and means interconnecting said exhaust controlling valves whereby the closing of one valve will cause opening of the other valve.
- 30 10. In a pump, a pair of adjacent cylinders provided with inlets for inlet of fluid to be pumped, a piston in each cylinder, means connecting said pistons, pumping chambers in said cylinders at the outer ends of said pistons, means 35 for supplying motive fluid to said cylinders at the inner ends of the pistons for causing movement of the pistons, valves for controlling the exhaust of motive fluid from said cylinders, means whereby the motive fluid supplied to either cylinder will cause closing of the exhaust 40 controlling valve of such cylinder and opening of the exhaust controlling valve of the other cylinder.
- 45 11. In a pump, a pair of adjacent cylinders having inlets for fluid to be pumped, a piston in each cylinder acting as a pumping piston and a power piston, means connecting said pistons, means for supplying motive fluid to said cylinders at one end of said pistons, valves for controlling the supply of motive fluid to said cylinders, independent means operated by each piston for 50 operating the valves controlling the delivery of motive fluid to the cylinders, said valve operating means and said valves arranged whereby each piston will actuate the valves to cut off the supply of motive fluid to its cylinder and open the supply to the other cylinder, a liquid discharge pipe 55 connected to the upper ends of said cylinders, means for conducting the liquid pumped from the cylinders and discharging it at an elevated point within said discharge pipe, and means for conducting and discharging the exhaust motive fluid from the cylinders into said liquid discharge pipe at a point below the point of discharge of the pumped liquid therein.
- 60 12. In a deep well pump, a pair of cylinders, a piston in each cylinder, means connecting said pistons, means for supplying motive fluid to said cylinders at one end of said pistons, valves for controlling the supply of motive fluid to said cylinders, independent means operated by each piston for 65 operating the valves controlling the delivery of motive fluid to the cylinders, said valve operating means and said valves arranged whereby each piston will actuate the valves to cut off the supply of motive fluid to its cylinder and open the supply to the other cylinder, a liquid discharge pipe connected to the upper ends of said cylinders, means for conducting the liquid pumped from the cylinders and discharging it at an elevated point within said discharge pipe, and means for conducting and discharging the exhaust motive fluid from the cylinders into said liquid discharge pipe at a point below the point of discharge of the pumped liquid therein.
- 70 13. In a deep well pump, a pair of cylinders, a piston in each cylinder, means connecting said pistons, means for supplying motive fluid to said cylinders at the inner ends of the pistons for causing movement of the pistons, said motive fluid supplying means including valves for controlling the supply of motive fluid to said cylinders, reciprocable push rods projecting into said cylinders for actuation by said pistons on their outward pumping movements for actuating said valves to cut off the supply of motive fluid from either cylinder when the piston therein approaches its outward limit of movement, and 10 means connecting said valves, whereby the movement of one valve to cut off the supply of motive fluid to one cylinder will open the other valve to admit motive fluid to the other cylinder.
- 15 14. In a deep well pump, a pair of cylinders, a piston in each cylinder, means for supplying motive fluid to said cylinders at the inner ends of the pistons for causing movement of the pistons, means connecting said pistons whereby movement of one piston under power of motive fluid will move the other piston said motive fluid supplying means including valves for controlling the supply of motive fluid to said cylinders, reciprocable push rods projecting into said cylinders for actuation by said pistons on their outward pumping movements for actuating said valves to cut off the supply of motive fluid from either cylinder when the piston therein approaches its outward limit of movement, means connecting 20 said valves whereby the movement of one valve to cut off the supply of motive fluid to one cylinder will open the other valve to admit motive fluid to the other cylinder, valves for controlling the exhaust of motive fluid from said cylinders, and means whereby the motive fluid supplied to either cylinder will cause closing of the exhaust controlling valve of such cylinder and opening 25 of the exhaust controlling valve of the other cylinder.
- 30 15. In a deep well pump, a pair of cylinders having inlets for fluid to be pumped, a piston in each cylinder acting both as a pumping piston and a power piston, means connecting said pistons, means for supplying motive fluid to said cylinders for moving said pistons, a liquid discharge pipe connected to the upper ends of said cylinders, means for conducting the liquid pumped from the cylinders and discharging it at an elevated point within said discharge pipe, and means for conducting and discharging the exhausted motive fluid from the cylinders into said liquid discharge pipe at a point below a point of discharge of the pumped liquid therein.
- 35 16. In a deep well pump, a pair of cylinders having inlets for liquid to be pumped, a piston in each cylinder acting both as a pumping piston and a power piston, means connecting said pistons, means for supplying motive fluid to said cylinders for moving said pistons, a liquid discharge pipe connected to the upper ends of said cylinders, means for conducting the liquid pumped from the cylinders and discharging it at an elevated point within said discharge pipe, means for conducting and discharging the exhausted motive fluid from the cylinders into said liquid discharge pipe at a point below a point of discharge of the pumped liquid therein, and means operated by incoming motive fluid to said cylinders for controlling the exhausting of 40 motive fluid from said cylinders.
- 45 17. In a deep well pump, a pair of adjacent cylinders, a piston in each cylinder acting as both a power piston and a pump piston, valves for controlling the delivery of motive fluid to said cylinders.

- ders, independent means operated by each piston for opening said valves, means connecting said valves whereby the opening of one valve will close the other one, and means connecting said pistons whereby pump discharging movement of one piston under power of motive fluid will move the other piston in pump suction movement.
17. In a deep well pump, a pair of adjacent cylinders, a piston in each cylinder acting as both a power piston and a pump piston, means connecting said pistons, valves for controlling the delivery of motive fluid to said cylinders, means operated by said pistons for opening said valves, means interconnecting said valves whereby the opening of one valve will close the other valve, valves controlling the exhaust of motive fluid from said cylinders, and means whereby the operating of said motive fluid supply control valves will operate said exhaust control valves.
18. In a deep well pump, a pair of adjacent cylinders, a piston in each cylinder acting as both a power piston and a pump piston, means connecting said pistons, valves for controlling the delivery of motive fluid to said cylinders, means operated by said pistons for opening said valves, means interconnecting said valves whereby the opening of one valve will close the other valve, valves controlling the exhaust of motive fluid from said cylinders, means whereby the operating of said motive fluid supply control valves will operate said exhaust control valves, and means connecting said exhaust valves whereby the closing of one exhaust valve will mechanically open the other exhaust valve.
19. In a deep well pump, a pair of adjacent cylinders having inlets for fluid to be pumped, a piston in each cylinder acting as both a power and a pumping piston, valves for controlling the delivery of motive fluid to said cylinders, means operated by said pistons for opening said valves, a pivoted lever interconnecting said valves whereby the opening of one valve will close the other, and flexible means connecting said pistons whereby pump discharging movement of one piston under power of motive fluid will move the other piston in pump suction movement.
20. In a deep well pump, a pair of adjacent cylinders having inlets for liquid to be pumped, a piston in each cylinder acting as both a power and a pumping piston, means connecting said pistons, valves for controlling the delivery of motive fluid to said cylinders, means operated by said pistons for opening said valves, a pivoted lever interconnecting said valves whereby the opening of one valve will close the other, valves controlling the exhaust of motive fluid from said cylinders, means whereby the operating of said motive fluid supply control valves will operate said exhaust control valves, and a pivoted lever connecting said exhaust control valves whereby the closing of one exhaust valve will open the other exhaust valve.
21. In a deep well pump, a cylinder block having a pair of parallel cylinders therein, said cylinders having inlets for fluid to be pumped, a piston in each cylinder, means connecting said pistons, said cylinder block provided with motive fluid passages communicating with the inner ends of said cylinders and acting alternately as fluid supply and exhaust passages, said pump provided with passages for fluid to be pumped communicating with the upper or outer ends of said cylinders, selective valves controlling the delivery of motive fluid into said motive fluid passages, and means operated by said pistons for operating said valves whereby one piston will open a valve to admit motive fluid to the cylinder of the other piston.
22. In a deep well pump, a cylinder block having a pair of parallel cylinders therein, said cylinders having inlets and outlets for liquid to be pumped, a piston in each cylinder, means connecting said pistons, said cylinder block provided with motive fluid passages communicating with the inner ends of said cylinders and acting alternately as fluid supply and exhaust passages, distributor blocks at one end of said passages and provided with passageways for controlling the inlet of motive fluid to the passages and with other passageways for controlling the exhaust of motive fluid from said passages, valves cooperating with said distributing blocks for controlling the exhaust passages in said distributing blocks, valves for controlling the delivery of motive fluid to said passages, means for operating said fluid delivery control valves, and means whereby the operation of said motive delivery control valves will control operation of said exhaust valves.
23. In a deep well pump, a cylinder block having a pair of parallel cylinders therein, said cylinders having inlets and outlets for liquid to be pumped, a piston in each cylinder, means connecting said pistons, said cylinder block provided with motive fluid passages communicating with the inner ends of said cylinders and acting alternately as fluid supply and exhaust passages, distributor blocks at one end of said passages and provided with passageways for controlling the inlet of motive fluid to the passages and with other passageways for controlling the exhaust of motive fluid from said passages, valves cooperating with said distributing blocks for controlling the exhaust passages in said distributing blocks, valves for controlling the delivery of motive fluid to said passages, means for operating said fluid delivery control valves, means whereby the operation of said motive delivery control valves will control operation of said exhaust valves, a liquid discharge pipe connected to the upper ends of said cylinders, means for conducting the liquid pumped from the cylinders and discharging it at an elevated point within said discharge pipe, and means for conducting and discharging the exhausted motive fluid from the cylinders to said liquid discharge pipe at a point below the point of discharge of the pumped liquid therein.
24. In a deep well pump, a cylinder block having a pair of parallel cylinders therein, said cylinders having inlets and outlets for liquid to be pumped, a piston in each cylinder, means connecting said pistons, said cylinder block provided with motive fluid passages communicating with the inner ends of said cylinders and acting alternately as fluid supply and exhaust passages, distributor blocks at one end of said passages and provided with passageways for controlling the inlet of motive fluid to the passages and with other passageways for controlling the exhaust of motive fluid from said passages, valves cooperating with said distributing blocks for controlling the exhaust passages in said distributing blocks, valves for controlling the delivery of motive fluid to said passages, means for operating said fluid delivery control valves, means whereby the operation of said motive delivery control valves will control operation of said exhaust valves, a liquid discharge pipe connected to the upper ends of said cylinders, means for conducting the liquid pumped from the cylinders and discharging it at an elevated point within said discharge pipe, and valved liquid

inlet connections for inlet of fluid to be pumped to the cylinders communicating with said last named means.

25. In a deep well pump, cylinders, pistons therein, means connecting said pistons, valves for controlling the delivery of piston moving fluid to said cylinders, push rods moved by said pistons in valve opening movement, and springs for moving said rods out of valve opening movement.

26. In a deep well pump, cylinders, pistons therein, means connecting said pistons, valves for controlling the delivery of piston moving fluid to said cylinders, push rods moved by said pistons in valve opening movement, and springs for moving said rods out of valve opening movement, said rods composed of telescoping yieldably connected sections.

JAMES PHILLIP JACKSON.
